WEAVING FRAME

Anna J. Haglund, Los Angeles, Calif., assignor of
one-third to Charles E. Haglund and one-third
to Antoinette J. Haglund, Los Angeles, Calif.

Application October 19, 1938, Serial No. 235,788

3 Claims. (Cl. 139—34)

5 My invention relates to weaving frames such as a person can hold in her hands, or her lap, or on a table in front of her and can move conveniently as she weaves the design, pattern or other needle work made thereon.

10 My invention relates to a weaving frame on which a foundation or net-like structure can be made in the frame, and in which foundation or net-like structure the particular design, pattern, or needle work is then woven or created.

15 The principal object of my invention is to provide a simple, practical and economical frame structure having four rods supported detachably therein and on which the strands or threads can be placed in creating the foundation, said four rods being in square or rectangular form and each being separately and quickly detachable, as may be desired.

20 Another object of my invention is to provide in a frame of the character referred to a frame structure with one or more rods or members formed to give a scallop edge, or an edge of varying curves or angles, as may be desired, as is sometimes given to lace collars, doilies, and the like.

25 Another object of my invention is to provide a weaving frame having an adjustable border or edge member extended across the frame between opposite sides thereof at different widths so that work of various sizes can be on one frame.

30 In order to explain my invention more in detail, I have illustrated the same on the accompanying sheet of drawings which I will now describe.

35 Figure 1 is a plan view of a weaving frame embodying my invention;

Figure 2 is a fragmentary sectional view taken on line 2—2 of Fig. 1;

40 Figure 3 is a partial view of a weaving frame similar to that shown in Fig. 1 and showing a scallop forming member in place in the frame;

Figure 4 is a similar view showing an adjustable scallop forming member thereon; and

45 Figure 5 is a fragmentary sectional view thereof taken on the line 5—5 of Fig. 4; and

Figure 6 is a partial view of a weaving frame having a scallop forming member in place in one side of the frame.

50 Referring now to the drawing in detail, I provide a base frame 1, shown to be square in this application, but not limited to a square form and having mounted on each corner a block or member, as 8, having a hole in one side to receive the end of a rod 9, inserted endwise therein, and

55 having therein, at right angles to said hole, an

other hole opening out at the top of said block, and designated 10, as will be clear from Fig. 2. The first hole is designated 8'.

Thus four rods, as 9, each have one end inserted endwise into a hole or bore, as 8' in one side of each block, and its other end laid laterally down in the open hole or slot 10, as indicated, whereby it is easy to remove each of said rods by lifting one end up out of the slot 10, and then withdrawing its other end from the hole 8'.

In Fig. 3, I have shown a scallop member 11, having at its opposite ends two short sleeves, as 12, 12, threaded on the rods, 13, 14, and in its middle having an extension 15, with a sleeve 15' on the rod 16, said scallop member having a 15 series of curved segments, as 11'. Said scallop member may be provided on its upper side with spaced thread-receiving pins or studs, as 17.

In Fig. 4, I have shown another scallop member 18, having the short sleeves 19, 19, at its 20 opposite ends, with set screws 20, so that said member can be adjusted along the rods 21, 21, as desired.

In Fig. 6, I have shown a weaving frame with one of the rods removed and a scallop member 25 23 inserted in its place and having its opposite ends inserted in the opposite blocks 8, 8, as clearly shown in said figure, said scallop border member having its upper side spaced pins or studs, as 24 to receive the loops of the threads or 30 strands, designated S in all figures.

In Fig. 1, it will be seen that the threads or strands S are arranged in crossed relationship, like a screen, and are tied together at each crossing, and thus a net or foundation is created on 35 the frame, so that any desired design or pattern can be woven or made thereon, as indicated by the shaded portions on said Fig. 1.

If the scallop member shown in Figs. 3 and 4, or in Fig. 6, is used, it will be clear that the woven 40 piece will be formed with scalloped edge. It will also be clear that these scallop members can be made in any desired form or design for the purpose of determining the form of the scalloped edges of the work turned out on the frame. 45

Thus I have provided a simple and practical weaving frame in which the rod members can be easily and quickly detached at will, rod members formed to provide for scallop edges can be substituted, and scallop members can be threaded 50 on or connected to opposite rod members to make possible work of different widths with scallop edge, as indicated in Figs. 3 and 4 of the drawing.

I do not limit my invention to the details of construction and arrangement shown and de- 55

scribed, except as I may be limited by the hereto appended claims forming a part hereof.

I claim:

- 5 1. In a weaving frame, a four sided frame member, means at each corner thereof having receiving openings in the same plane for holding work-holding members extending from one corner to an opposite corner, whereby to form a frame to receive work, and four work-holding members detachably held in said openings at each corner, opposite work-holding members being of undulating form formed to form scallop edges in the work.
- 10 2. A weaving frame including a frame, corner

members at each corner on the top surface thereof of having openings in the same plane at right angles to each other to hold rods, rods detachably held at their opposite ends in said openings, and scallop members adjustably connected at 5 their opposite ends to opposite frame members to form scallop edges on the work.

3. A weaving frame including a frame, corner members at each corner, work holding rods detachably held in the same plane between said 10 corner members, and scallop members of undulating form connected to opposite rods, across said frame member, for the purpose described.

ANNA J. HAGLUND.
